Attnys.

UNITED STATES PATENT OFFICE.

HAMILTON LINDSAY, OF CLEVELAND, OHIO, ASSIGNOR TO THE LINDSAY WIRE WEAVING COMPANY, OF CLEVELAND, OHIO, A CORPORATION OF OHIO.

SEAM FOR WOVEN-WIRE BELTS.

Application filed May 12, 1924. Serial No. 712,579.

This invention relates to means for joining the ends of a wire fabric to form an endless belt which is particularly useful on Fourdrinier paper machines. My invention is also adapted for use in connection with a belt having a special weave as set forth in my copending application Serial No. 525,403, filed December 28, 1921.

Briefly the belt illustrated in my copending application embodies a fabric wherein the lower knuckles of the longitudinally extending or warp wires pass continuously beneath two or more cross or woof wires instead of only one. Accordingly the warp wires are divided into two groups, each preferably of three wires in number during the weaving operation, and are so manipulated that one group forms one plane of the shed while the other two groups form the other plane of the shed, while the shuttle passes therebetween and across the loom. These groups are interchanged at each stroke of the shuttle, whereby the fabric so formed has short knuckles on the upper side thereof and long knuckles on the lower side thereof. This results in a construction which when formed into a belt gives a longer wearing surface to the under side of the belt, thereby increasing the life thereof.

One of the difficulties in joining the ends of a belt is the provision of a seam having sufficient strength to effect a strong joint yet which does not fill the interstices (which would render it difficult for water to pass through the seam when the belt is in use), and at the same time forms a sufficient support between the ends of the fabric so as not to strain the pulp.

Seams for joining the ends of woven wire belts have heretofore been made, but usually such seams require the use of a closing wire in addition to stitching wires which are intended to reinforce the end of the belt so as to prevent movement of the woof wires when the belt is in use.

Accordingly one of the objects of my invention is the provision of a seam having sufficient space for the passage of water therethrough and sufficient support between the ends of the fabric so that the pulp is properly drained and at the same time supported adjacent the seam, whereby the paper is not weakened. Furthermore my inven-

tion includes a seam, the wires of which lie in substantially the same plane as the warp wires, so that the wear occasioned by the passage of the seam across a suction box is not greater than that occurring on other parts of the belt.

Another object of my invention is the provision of a seam which eliminates the necessity for a closing wire independently of stitching wires, wherefore I eliminate one complete operation in the joining of a belt. This is advantageous, particularly since the width of a belt is usually 12 to 15 feet while the fabric is about sixty mesh, and since the sewing must be accomplished by hand.

The preferred embodiment for carrying out my invention is illustrated in connection with the accompanying drawings and is hereinafter described in detail. The essential features and characteristics are summarized in the claims.

In the drawings, Figs. 1 and 2 are plan views illustrating portions adjacent the ends of a belt having a weave constructed as heretofore described and illustrating a seam embodying my invention, wherein Fig. 1 shows the top side of the belt, while Fig. 2 shows the bottom side thereof; and Fig. 3 is a section taken on the line 3—3 in Fig. 1.

My invention is well adapted for use in joining the ends of a belt embodying any standard weave, but I have illustrated it in connection with the special weave described and claimed in my copending application. Accordingly by referring to the drawings the fabric is shown as having warp wires A¹, A², A³, etc., which are interwoven with woof wires at one end of the belt as indicated at B¹, B², B³, etc. The woof wires at the co-operating end of the belt are indicated at BB¹, BB², BB³, etc. The manner in which the weave is made is illustrated by the upper end of the belt in Fig. 1 wherein the warp wire A¹ passes over the woof wire B¹, then beneath two transverse wires B² and B³, over the wire B⁴, and then beneath the next two transverse wires of which only one is shown. The next warp wire indicated at A² passes beneath two woof wires B¹ and B², then over the wire B³, thence beneath the next two woof wires B⁴, B⁵, etc. The third warp wire A³ passes beneath the woof wire B¹, then over the woof wire B², thence beneath

the next two wires B^3 and B^4 , then over the wire B^5 , etc. The woof wires BB^1 to BB^5 respectively illustrated in the lower half of Fig. 1 are interwoven with the warp wires 5 in the same manner as illustrated for the upper half of the fabric shown in Fig. 1.

The fabric thus shown and described has warp wires which pass alternately over one woof wire and beneath two succeeding woof 10 wires, while the woof wires pass alternately over two and beneath one warp wire. This provides a belt having on its under side a series of long longitudinal or warp knuckles in contradistinction to the short or abrupt 15 knuckles on the upper side. This provides a weave wherein every third warp wire adjacent the same woof wire has a short knuckle on the upper side as is shown particularly in Fig. 1, wherein the wire B^4 has 20 short knuckles on the top side thereof indicated at 10 to 14 respectively. Similarly the wire B^3 on the top side of the fabric has short knuckles, each positioned one warp wire to the left of those forming the 25 short knuckles over the wire B^4 as indicated at 16 to 20 respectively. The corresponding short knuckles on the lower region of the belt are indicated on the woof wire BB^4 at 21 to 25, and on the wire BB^3 at 26 to 30 respectively.

The seam embodying my invention is illustrated as comprising a stitching wire S which extends around one end of the fabric to form loops adjacent the end of the belt. 35 This stitching wire is carried into the belt a sufficient distance to prevent unraveling when tension is placed thereon during use, and as shown has inner loops all of which pass over the same woof wire BB^4 . The 40 tendency of the stitching wire to displace the woof wire BB^4 is resisted by the rise of the wire A^2 which forms the short knuckle 26 and by the fall of the wire A^3 which forms the short knuckle 21. In this 45 way, the woof wire is not distorted when tension is placed upon the belt. The outer loops of the wire S are shown as passing over the woof wire BB^1 and in such position as to avoid the short knuckles on the top 50 and bottom sides of the fabric, wherefore the seam-forming wire lies in substantially the same plane as the warp wires. This has a tendency to increase the life of the belt by reducing the friction occasioned by the 55 travel of the belt over the suction boxes in a paper machine.

The upper half of the belt indicated in Fig. 1 has a seam-forming wire S^1 which passes through the belt over the woof wire 60 B^4 between warp wires, one of which has the rise of a short knuckle on one side thereof and the fall of a short knuckle on the other side thereof. For instance, the loop passing between the warp wires A^1 and A^2 65 has the fall of the short knuckle 10 on one

side and the rise of the short knuckle 16 on the other side thereof. In this way the seam forming wire S^1 has inner loops all of which pass over the same woof wire B^4 .

The outer loops of the wire S^1 , however, 70 extend across the end of the belt and are passed around the woof wire BB^1 , and through the outer loops on the wire S . This provides a seam wherein the wire S^1 serves as a closing wire, as well as a stitching- 75 wire.

An advantage of a seam made in accordance with my invention is that one end of the belt may be placed over the other after the wire S is previously woven into the fabric, whereupon the wire S^1 may be simultaneously interwoven through the end of the belt on which it serves as a reinforcing wire and also through the outer loops of the cooperating stitching wire. This eliminates the necessity for a third sewing operation, which is a material advantage since the belts are usually made of wire having sixty mesh, wherefore each seam-forming wire has about twenty loops within the belt 80 to the inch. The difficulty of making such a seam by hand is readily apparent.

A seam made in accordance with the present invention does not clog the space across the ends of the belt sufficiently to interfere with the drainage, and at the same time, does not provide too great a space so as to strain the pulp.

Having thus described my invention, I claim:—

1. A seam for woven wire fabric comprising two seam-forming wires, each of said wires extending back into the belt over a plurality of woof wires and each having inner loops and outer loops, the outer loops of one wire passing through the outer loops of the other wire.

2. A seam for woven wire fabric comprising a stitch-forming wire at each end of the belt, having inner loops and outer loops, and extending back into the belt over a plurality of woof wires, the loops of one stitching wire passing through the loops in the other stitching wire, and the loops of both wires passing around the same woof wire.

3. A seam for woven wire fabric comprising two seam-forming wires, each having inner loops and outer loops and each extending back into the belt over a plurality of woof wires, some of the outer loops of one wire extending across the seam opening and passing through the outer loops in the other wire.

4. A seam for woven wire fabric comprising two seam-forming wires, each having inner loops and outer loops and each extending back into the belt over a plurality of woof wires, some of the outer loops of one wire passing around the end woof wire, and

some of the outer loops of the other seam-forming wire passing across the seam opening and extending through the outer loops on the first-mentioned seam wire, and also 5 extending around said end woof wire.

5. A seam for woven wire fabric comprising two seam-forming wires, each having inner loops and outer loops, and each extending back into the belt over a plurality of 10 woof wires, the outer loops of each wire being looped around the same woof wire.

6. A seam for woven wire fabric comprising two seam-forming wires, each having inner loops and outer loops and each extending back into the belt over a plurality of 15 woof wires, the outer loops of each wire being interlocked around the same woof wire, whereby one seam-forming wire terminates at the end of the belt, while the 20 other extends across the seam opening.

7. A seam for woven wire fabric comprising two seam-forming wires, each having inner loops and outer loops and each extending back into the belt over a plurality of 25 woof wires, the outer loops being interlocked, the inner loops of one wire passing through the fabric over the same woof wire on one end of the belt, and the inner loops of the other wire passing over the same woof 30 wire on the opposite end of the belt.

8. A seam for an endless belt wherein the weave comprises warp wires and woof wires, the warp wires having long knuckles on one 35 side of the belt and short knuckles on the other side thereof, having two seam-forming wires, each having inner loops and outer loops and each extending back into the belt over a plurality of woof wires, the outer loops being interlocked and the inner loops

of at least one of the wires passing through 40 the belt adjacent a short warp knuckle.

9. A seam for an endless belt wherein the weave comprises warp wires and woof wires, the warp wires having long knuckles on 45 one side of the belt and short knuckles on the other side thereof, comprising two seam-forming wires, each having inner loops and outer loops and each extending back into the belt over a plurality of woof wires, the outer loops being interlocked over an end 50 woof wire, and the inner loops passing through the belt between two warp wires, one of which has the rise of a short warp knuckle, and the other of which has the fall of a short warp knuckle adjacent to the 55 loops.

10. A seam for an endless belt wherein the weave comprises warp wires and woof wires, the warp wires having long knuckles on one 60 side of the belt and short knuckles on the other side thereof, comprising two seam-forming wires, each having inner loops and outer loops and each extending back into the belt over a plurality of woof wires, each 65 inner loop passing through the belt in such manner that the woof wire over which the inner loops extend is disposed intermediate the rise of a short warp knuckle and the fall of another short warp knuckle, while 70 all of the inner loops of one seam-forming wire pass over the same woof wire on one end of the belt, and the inner loops of the other seam-forming wire pass over the same woof wire on the opposite end of the belt.

In testimony whereof, I hereunto affix my 75 signature.

HAMILTON LINDSAY.
